CENTRALIZED TRAFFIC CONTROLLING SYSTEM

Walter W. Wenholz, Rochester, N. Y., assignor to
General Railway Signal Company, Rochester,
N. Y.

Application January 28, 1931, Serial No. 511,829

17 Claims. (Cl. 246—3)

This invention relates to centralized traffic controlling systems, and more particularly to a system of the unit line wire type, as distinguished from the system of the selector type.

5 In accordance with the present invention, it is proposed to control a distant switch machine over one line circuit, to control signals associated with the track switch operated by such switch machine over another line circuit, and to indicate whether or not the track is occupied by a passing train and whether or not one of the various signals is indicating proceed, this through the medium of contacts at said track switch location, which open the line circuits used for controlling the switch machine and signals. It is of course apparent that if the clearing of a signal were to open the line circuit controlling such signal for indicating purposes, such signal could not be maintained clear without the provision of 10 suitable stick means. Also, if the clearing of a signal were to be indicated over the circuit used for controlling the switch machine, this switch machine control circuit would not be available for indicating the passage of a train over the 15 track switch; also, switch machine operation could not be indicated over the signal control circuit, because the signals must be held at stop to operate the switch machine.

In accordance with the present invention, it 20 is proposed to indicate over the switch control circuit the occupied or unoccupied condition of the detector track circuit associated with the track switch, and to indicate over the switch machine control circuit both the occupancy of 25 this detector track circuit and the clearing of the signal, from which it is apparent that, if the switch machine control circuit is open and the signal control circuit is closed, the switch machine control circuit must be open by reason of 30 the fact that one of the signals is at proceed.

Another feature of the present invention resides in the provision of means for indicating an inconsistency between the signal control relay energization and the indicating condition of the 35 signal controlled by such relay.

Other objects, purposes and characteristic features of the invention will in part be more specifically pointed out hereinafter, and will in part be obvious from the accompanying drawing.

40 In describing the invention in detail, reference will be made to the accompanying drawing, which shows conventionally the circuits and devices at an out-lying track switch location, and shows conventionally that portion of the central office equipment for controlling the switch and

signals at such location and receiving indications therefrom.

Referring to the drawing, the track rails of a railway system have been shown by the reference character 1, which rails are divided into 5 track circuit sections by insulating joints 2. These track sections are each provided with a track circuit in the usual way, of which the detector track circuit containing the detector track relay DT and a track battery 4 have only for 10 convenience been shown. Only a portion of the railway signalling system has been shown in the drawing, which portion includes one end of a passing siding PS and the end of a single track section O. Traffic may move from the single 15 track section O into the side track of the passing siding PS through the medium of a track switch SW, which is preferably power operated, as by the switch machine SM.

Although the signalling system to which the 20 present invention is applicable may be a signalling system of the double track type, in which traffic moves only in one direction on each track, the invention has been shown applied to a single track railway system in which traffic may move 25 in either direction in response to signal indications, this single track section being signalled by a signalling system of the absolute-permissive-block type.

This A. P. B. system preferably includes a 30 main starting signal 7 and a dwarf starting signal 7^d, which signals govern the movement of traffic off of the main track and the side track, respectively, into the single track section O, and this track switch SW also has associated therewith a main entering signal 8 and a take-siding signal 8^d. These signals 7, 7^d, 8 and 8^d are controlled in accordance with traffic conditions in 35 advance, as through the medium of home-and-distance relays 7HD and 8HD, and are further 40 manually controlled by the signal control relay SZ, the main track and side track signals being selected in accordance with the position of a manually controlled switch machine control relay WZ and a switch machine repeater relay 45 WP.

In order to indicate through the same circuits used for controlling these control relays SZ and WZ the condition of occupancy of the detector track circuit, as well as the initiation and completion of the stroke of the switch machine, a relay OS controlled through the following circuit has been provided:—beginning at the terminal (+) or (—) of the way station split battery, depending upon whether the switch machine SM 55

is in its locked or in an intermediate position as manifested by the switch machine repeater relay WP, contact 10 of this relay WP, wire 11, front contact 12 of the detector track relay DT, wire 13, 5 winding of the relay OS to the midpoint C of said battery. This switch machine repeater relay WP is energized by the following circuit:—beginning at the terminal (+) or terminal (—), depending upon whether the switch machine SM assumes 10 the main track or the side track position, switch machine contact 15, wire 16, winding of the relay WP to the midpoint C of the way station battery.

The switch machine SM is preferably cut out of service in the event that current has been 15 flowing through the switch machine motor for too long a time or an excessive amount of current has been flowing through this switch machine, and for this purpose the cut-out relay CO and the associated thermal relay TR have been provided.

Referring now to the central office equipment, this central office, or dispatcher's office, has been conventionally illustrated by the dotted rectangle DO, and in this central office the entire railway 25 system is preferably reproduced in miniature, as conventionally illustrated by the miniature passing siding ps corresponding in every detail to the actual passing siding PS. In this central office DO are located the necessary levers for controlling 30 the various switch machines and signals, and in the particular arrangement shown only the signal lever LS and the switch lever LW, and their associated contacts and relays have been illustrated. The signal lever LS is connected to the signal 35 control relay SZ through the medium of the line wire 20 and includes in series therewith an indicating relay IR¹, and the switch lever LW is connected to the switch control relay WZ through the medium of a line wire 21, which has included in 40 series therewith an indicating relay IR² located in the central office DO. The indicating relay IR² has associated therewith a slow acting repeater relay RR which is slow to pick up.

The switch control lever LW is normally left 45 in the main track position, in which it has been shown, and in which position the switch control relay WZ is energized toward the right through the following circuit:—beginning at the terminal (+) of the central office split battery, switch 50 lever LW, wire 23, winding of the indicating relay IR², line wire 21, front contact 24 of the relay OS, wires 25 and 26, back contact 27 of the relay SZ, wire 28, winding of the relay WZ to the common 55 return wire C connected to the midpoint of the central office battery. Also, under normal conditions of the apparatus the cut-out relay CO is energized through the following circuit:—beginning at the terminal (+) of the way station battery, wire 30, contact 31 of the thermal 60 relay TR, wire 32, winding of the relay CO, wires 33 and 34, stick contact 35 to the other terminal (—) of said battery. The current thus flowing through element 105 is insufficient to cause it to open the contact 31.

65 Although the normal circuit for the switch machine including the normal wire N appears to be closed, this circuit is broken within the switch machine SM, this switch machine preferably being one of the type shown in the patent to Howe No. 1,466,903 dated September 4, 1923, wherein the operating circuits are broken upon completion of the stroke of the switch machine. It is believed that the novel features of the system as well as its operating characteristics 70 are more readily understood by considering the

operation of the system, which will now be taken up.

Operation

It is, of course, understood that the track switch SW assumes its main track position, and let us further assume that there is an east bound train moving in the single track section O, and that the operator wishes this train to move into the main track of the passing siding PS. In order to accomplish such east bound train movement, the operator will move his lever LS to the right, thereby energizing the signal relay SZ to its right hand energized position through the following circuit:—beginning at the terminal (+) 10 of the central office split battery, signal contact LS, wire 40, winding of the indicating relay IR¹, line wire 20, front contact 41 of the relay OS, wire 42, winding of the relay SZ, through the common return wire C connected to the midpoint 15 of the central office battery.

The completion of this circuit will of course energize the relay SZ to the right, thereby lifting its back contact 27 and opening the circuit for the indicating relay IR², and thereby allowing the contact 44 of the indicating relay IR² to drop to its retracted position and opening the circuit (from minus, finger 44 and front point, wire 81, lamp EI, wire 80, lever 45, wire 79, finger 46 and front point, wire 78, lever 77, to plus) for the east bound indicating lamp EI, which circuit would have been closed through the medium of the signal lever contact 45 and the front contact 46 of the indicating relay IR¹, from which it is apparent that the east bound indicating lamp EI is still extinguished. With the signal relay SZ 20 now assuming its energized position the signal 25 8 will be cleared through the following circuit:—beginning at the terminal (+) of the way station battery, front contact 48 of the detector track relay DT, wire 49, front contact 50 of the relay SZ, wire 51, polar contact 52 of the relay SZ assuming its right-hand position, wires 53 and 54, polar contact 55 of the relay WZ, wire 56, neutral contact 57 of the relay WP, wire 58, polar contact 59 of the relay WP, wire 60, neutral contact 61 of the home-and-distance relay 8HD, polar contact 62 of the relay 8HD, assuming its solid line or dotted line position depending on traffic conditions ahead, and through the clear or caution wire for the signal 8 conventionally 30 shown by the dotted line 63.

Clearing of the signal 8, by the opening of its semaphore contact 66 will break the energizing circuit for the signals-at-stop relay M, the circuit for which relay may be traced as follows:—beginning at the terminal (+) of the way station battery, semaphore contact 61 of the signal 7 closed only when this signal assumes the stop position, wire 68, signal contact 69 of the signal 7^d closed only when this signal 7^d is at stop, wire 70, contact 66 of the signal 8, wire 71, contact 72 of the take-siding signal 8^d closed only when this signal 8^d is at stop, wire 73, winding of the relay M to the other terminal (—) of the way 40 station battery.

The breaking of this circuit at the contact 66 causes the relay M to assume its deenergized position, thereby effecting closure of its back contact 75 and effecting reenergization of the indicating relay IR², (through a circuit including plus, lever LW, wire 23, relay IR², wire 21, finger 24 and front point, wire 25, finger 75 and back point, wire 28, relay WZ, to common) thereby completing the following circuit for the east bound indi- 45 75

cating lamp EI:—beginning at the terminal (+) of the way station battery, contact 77 of the lever LW, wire 78, front contact 46 of the relay IR¹, wire 79, contact 45 of the lever LS, wire 80, indicating lamp EI, wire 81, front contact 44 of the relay IR² to the other terminal (—) of said central office battery.

In response to this clearing of the signal 8, the train under consideration may, of course, move from the single track section O into the main track of the passing siding PS. As this train passes the signal 8 and treads upon the detector track circuit containing the track relay DT, this track relay DT is deenergized, thereby opening its contacts 12, 48 and 65. Contact 48 is included in the clear and caution circuit for the signal 8, so that the signal 8 will be actuated to its stop position; the contact 65 is included in the clearing circuit for the take-siding signal 8^d, and the contact 12 of this relay DT by its dropping opens the energizing circuit for the relay OS, which in turn breaks both of the line circuits 20 and 21 through the medium of its contacts 41 and 24.

25. Simultaneous breaking of the two line circuits 20 and 21 causes the indicating relays IR¹ and IR² to simultaneously move to their deenergized position. Dropping of the indicating relay IR² effects extinguishment of the indicating lamp EI and energization of the slow acting repeater relay RR, but by reason of the slow acting characteristic of this relay RR its contact 83 will for a time remain in its retracted position, thereby momentarily completing the following circuit for sounding the bell, or other suitable audible signal, BL:—beginning at the terminal (+) of the central office battery, contact 77 of the switch control lever LW, wire 78, back contact 46 of the relay IR¹, wire 84, back contact 85 of the relay IR², wire 86, back contact 83 of the repeater relay RR, wire 87, bell cut-out key 88, wire 89, winding of the bell BL, to the other terminal (—) of said central office battery. Completion of this circuit sounds the audible signal BL and after a short 45. period of time the contact 83 will have been operated to its attracted position, thereby completing the following circuit for the detector track circuit occupancy lamp I:—beginning at the terminal (+) of the central office battery, elements 77, 78, 46, 84, 85, 86, 83, and 90, track occupancy indicating lamp I, to the other terminal (—) of the central office battery. The operator at the central office is therefore informed by the extinguishment of his east bound indicating lamp EI that the signal 8 has been moved to the stop position, and has further been informed by the sounding of the audible signal BL and the illumination of the indicating lamp I that the train in question has entered upon the detector track circuit containing the track relay DT.

60. As soon as the rear end of the train under consideration passes off of this detector track circuit the delay OS is energized and the contacts 41 and 24 are reclosed. Reclosure of the contact 41 effects reenergization of the relays IR¹ and SZ, but reclosure of the contact 24 will not effect reenergization of the relays IR² and WZ, because the signals-at-stop relay M is now again energized, the signal 8 having been moved to stop, so that the contact 75 of this relay M is open, as is also the contact 27 of the relay SZ, so that the indicating relay IR² remains deenergized. With the relay IR² in the central office DO deenergized and the indicating relay IR¹ in the central office 75. DO energized, none of the indicating lamps I,

WI or EI in the central office can be illuminated, as is readily apparent by observing the circuits for these indicating lamps.

As soon as the train in question has moved beyond the danger distance signified by the stop position of the home-and-distance relay 8HD, this signal 8 will be moved to caution, and with the signal 8 at caution the opening of its contact 66 will effect deenergization of the relay M, thereby reclosing the circuit including the line wire 21 10 and effecting reenergization of the indicating relay IR². With the indicating relays IR¹ and IR² both energized the east bound indicating lamp EI is again illuminated through the medium of the circuit heretofore traced. From the foregoing consideration it is apparent that a continuing indication of the occupancy of the detector track circuit containing track relay DT is indicated by continued illumination of the track occupancy indicator lamp I, and that the 15 movement of any one of the signals 7, 7^d, 8 and 8^d from the stop position is continuously indicated by the indicating lamps WI or EI depending upon the direction governed by the signal which is assuming a proceed position. Further, it will be 20 noted that the signal 8 could not be cleared or operated to caution unless the relays WZ and WP, which respectively control, and are controlled by, the switch machine SM, assume corresponding 25 positions.

30. For a train moving in a westwardly direction from the main track of the passing siding PS into the single track section O, the operation of the apparatus is identical to that just considered, except that the polar-neutral signal control relay 35 SZ is energized to its left hand position, thereby completing the following energizing circuit for the signal 7:—beginning at the terminal (+) of the way station battery, front contact 48 of the detector track relay DT, elements 49, 50, 51, 52, 40 92, 93, 94, 95, 96, 97, 98, 99, 100, the caution or clear wire for the signal 7 conventionally indicated by the dotted line 101, to the other terminal (—) of the way station battery.

45. Let us now assume that there is a west bound train on the side track of the passing siding PS and that the operator, or dispatcher, wishes to allow this train to proceed into the single track section O. The operator will of course first place the signals in the stop position by operating the 50 signal lever LS to its middle position, this in order to allow certain time or approach locking means to function to permit operation of the switch machine, this time or approach locking means having for convenience been omitted from the drawing, but being shown in the prior application of Wight Ser. No. 120,423 filed July 3, 1926. The operator will then move his switch lever LW to the dotted position, and thereby will operate the switch control relay WZ to its left hand dotted 55 position through the circuit heretofore traced, except that this circuit is now energized by current of negative polarity.

60. With the polar-neutral switch control relay WZ operated to its left hand position, the following 65 circuit for operating the switch machine SM to its reverse take-siding position is closed:—beginning at the terminal (+), front contact 103 of the relay CO, wire 104, heating coil 105 of the thermal relay TR, wire 106, front contact 107 70 of the relay WZ, wire 108, polar contact 109 of the relay WZ assuming its left hand position, reverse wire R to the midpoint C of the way station battery. Closure of this circuit will effect operation of the switch machine SM to its take-siding position 75.

tion, and when the switch machine SM has completed its operating stroke and has been locked up the circuit just traced is again broken by contacts associated with the switch machine itself. The contact 15 in the switch machine is moved to an intermediate position upon initiation of movement of the switch machine and remains in the intermediate position until the switch has completed its operating stroke and has again been locked up, at which time this contact assumes its other extreme position, so that the switch machine repeater relay WP is deenergized as soon as the switch machine SM is initiated upon its operating stroke.

15 This dropping of the relay WP reverses the direction of current flow through the relay OS, so that this relay OS is momentarily deenergized because the magnetism within its core structure must pass through zero and thereby momentarily drop its armature. This momentary dropping of the armature of the relay OS effects momentary opening of the contacts 24 and 41, but since the signal lever LS is in its intermediate position the opening of the contact 41 serves no function at this time. Momentary opening of the contact 24 will effect momentary deenergization of the indicating relay IR², and this momentary deenergization of the indicating relay IR² will effect momentary sounding of the audible signal 25 BL and momentary flashing of the indicating lamp I, all for reasons heretofore explained and stating it briefly is accomplished by dropping of the contact 85 of the relay IR² and picking up of the contact 83 of the repeater relay RR, there 30 being a slight additional delay in the operation of the contact 83 after operation of the contact 85. Also, if desired the relay RR may be sufficiently slow acting as compared with the relay OS that no flash of the lamp I is given at this 35 time. As the switch machine completes its operating stroke the switch machine repeater relay WP is reenergized, but at this time is energized to its left hand position, and the reenergization of the relay WP again effects momentary deenergization of the relay OS, this because the direction of current flow in the relay OS is again reversed.

The operator having now been informed of the completion of the stroke of the switch machine, and since, as has been assumed, he desired to set up west bound traffic off of the side track of the passing siding PS, he will operate his signal lever LS to the left hand position, thereby energizing the signal relay SZ to its left hand energized position, under which condition the following circuit for the dwarf starting signal 7^d is closed:—beginning at the terminal (+) of the way station battery, front contact 48 of the detector track relay DT, elements 49, 50, 51, 52, 53, 60 55 56, 111, 97, 96, 95, 94, 112, front contact 113 of the home-and-distant relay 7HD, polar contact 114 of this same relay through the clear or caution wire for the dwarf signal 7^d depending on the extent of unoccupied track ahead as manifested by 65 the position of the polar contact 114 of the relay 7HD, through the mechanism of the dwarf signal 7^d, to the other terminal of the way station battery.

Clearing of this signal 7^d will allow the train 70 to move off of the side track into the single track section O, and this movement of the train will be indicated through the medium of the track occupancy indicator I in the central office DO, and also the clearing of the signal 7^d will be indicated at the central office through the medium 75

of the west bound indicator WI, this signal lamp WI being controlled through the medium of the wire 115 instead of wire 80 of the circuit heretofore traced for the indicating lamp EI. It is readily understood that the take-siding signal 8^d is controlled in accordance with the position of the relays SZ, WZ and WP and in accordance with the position of the contact 65 of the detector track relay DT, all in a manner readily indicated by the contacts of these various relays. 10

Attention is particularly directed to the fact that none of the signals 7, 7^d, 8, or 8^d can be clear unless the relays WZ and WP, respectively controlling, and controlled by, the switch machine SM, assume corresponding positions. It 15 will be noted that these various signal circuits include neutral contacts of the switch machine relay WP but do not include neutral contacts of the switch machine control relay WZ; the neutral contacts of the relay WZ have been omitted 20 for the reason that the relay WZ is at times deenergized, as for instance when the signals are at stop and the contact 75 of the relay M assumes its raised position. Further with relay SZ energized to clear a signal the contact 27 is open, 25 under which condition it is apparent that the signals could not be cleared if neutral front contacts of the relay WZ were included in the signal control circuits. The signal circuits are so organized that polar contacts of the relays WZ 30 and WP must assume corresponding positions, so that if the switch machine should not complete its stroke or should not at all respond to a change in the position of its control relay WZ, it would result in holding all of the signals associated with the track switch SW at stop. 35

Applicant has thus provided a circuit arrangement in which the condition of track occupancy is transmitted over one line circuit, namely through the medium of the indicating relay IR¹, 40 and the condition of track occupancy as well as the condition of signal clearing is indicated over another line circuit, as through the medium of indicating relay IR². It is therefore possible to interpret at the central office the indicating condition of the signals located at the distant track switch, this by comparing the indications received over the two line circuits, which comparison is accomplished through the medium of the slow acting repeater relay RR and the 45 various contacts associated with the relays IR¹, IR² and RR. 50

Having thus shown and described one rather specific embodiment of the present invention, it is desired to be understood that the particular 55 circuit arrangement illustrated in the drawing has not been selected for the purpose of showing the scope of the invention, nor has it been selected for the purpose of illustrating the construction preferably employed in practicing the 60 invention, but has been selected for the purpose of facilitating disclosure of the underlying principles and operating characteristics of a system embodying the present invention, and it is further desired to be understood that various changes, 65 modifications and additions may be made to adapt the invention to the particular problem encountered in practicing the invention all without departing from the spirit or scope of the invention or the idea of means underlying the same, 70 except as demanded by the scope of the following claims.

What I claim as new is:—

1. In a centralized traffic controlling system, in combination, a central office and a distant track 75

switch, signals associated with said track switch, a switch machine for operating said track switch, a switch control circuit including the contact of a lever and for controlling said switch machine, 5 a signal control circuit including the contact of a second lever and for controlling said signals, means for indicating occupancy of a section including said track switch over said signal control circuit, and means for indicating over said switch 10 control circuit the proceed condition of a signal when a section including said track switch is unoccupied.

2. In a centralized traffic controlling system, the combination with a central office and a distant track switch, signals associated with said track switch, and a switch machine for operating said track switch, of a switch control line circuit including a contact of a lever and for controlling said switch machine, a signal control line circuit 20 including a contact of a second lever and for controlling said signals, means in said central office for indicating the continuity of said signal control circuit, means in said office for indicating the continuity of said switch control circuit, means 25 for opening said signal control circuit during occupancy of a section including said track switch, and means for opening said switch control circuit when all of said signals indicate stop and the section including said track switch is unoccupied providing said signal control circuit is energized.

3. In a centralized traffic controlling system, in combination, a central office, and a distant track switch, signals associated with said track switch, a switch machine for operating said track switch, a switch control line circuit for controlling said switch machine, a signal control line circuit for controlling said signals, means in said central office for indicating the continuity of said signal control circuit, means in said office for indicating the continuity of said switch control circuit, means for opening said signal control circuit during occupancy of a section including said track switch, a signal control relay in said signal control circuit, and means for opening said switch control circuit when said section is unoccupied and also said signal control relay is out of correspondence with the signal controlled by said signal control relay.

50 4. In a centralized traffic controlling system, the combination, with a central office and a distant track switch, signals associated with said track switch, and a switch machine for operating said track switch, of a switch control circuit including a switch lever contact and for controlling said switch machine, a signal control circuit including a signal lever contact and for controlling said signals, means for indicating occupancy of a section including said track switch over said signal control circuit, and means effective if said signal control circuit is energized to clear one of said signals and to render said switch control circuit effective to indicate if such signal has been cleared.

65 5. In a centralized traffic controlling system, the combination with a central office and a distant track switch, signals associated with said track switch, and a switch machine for operating said track switch, of a switch control line circuit including a switch lever contact and for controlling said switch machine, a signal control line circuit including a signal lever contact and for controlling said signals, means for opening said switch control circuit when all of said signals indicate stop, means for opening said sig-

nal control circuit when said track switch is occupied by a train, a signal-at-proceed indicator at said central office rendered effective when neither of said control circuits has been opened, and a track switch occupancy indicator rendered effective if both of said line circuits have been opened.

6. In a centralized traffic controlling system, the combination with a central office and a distant track switch, signals associated with said track switch, a switch machine for operating said track switch, a switch control line circuit for controlling said switch machine, a signal control line circuit for controlling said signals, means for opening said switch control circuit when all of said signals indicate stop, means for opening said signal control circuit when said track switch is occupied by a train, two signal-at-proceed indicators at said central office one of which is rendered effective when neither of said control circuits has been opened, a track switch occupancy indicator rendered effective if both of said line circuits have been opened, and means for selecting a particular one of said two indicators depending on the position of a control lever for controlling energization of said signal control circuit.

7. In a centralized traffic controlling system, the combination with a central office and a distant track switch, a signal associated with said track switch, a switch machine for operating said track switch, a switch control circuit including a switch lever contact and for controlling said switch machine, a signal control circuit including a signal lever contact and for controlling said signals, and means for indicating occupancy of a track section including said track switch over said signal control circuit.

8. In a centralized traffic controlling system, the combination with a central office and a distant track switch, signals associated with said track switch, and a switch machine for operating said track switch, of a switch control circuit including a switch control lever and for controlling said switch machine, a signal control circuit including a signal control lever and for controlling said signals, and means for indicating over said switch control circuit the proceed condition of a signal when a section including said track switch is unoccupied.

9. In a centralized traffic controlling system, the combination with a central office and a distant track switch, a signal associated with said track switch, a switch machine for operating said track switch, a switch control circuit including the contacts of a switch control lever for controlling said switch machine, a signal control circuit including the contacts of a signal control lever and for controlling said signals, and means for indicating over said signal control circuit the initiation of operation and the completion of the stroke of said switch machine.

10. In a centralized traffic controlling system, the combination with a central office and a distant track switch, signals associated with said track switch and a switch machine for operating said track switch, of a switch control circuit controlled by a track switch lever and for controlling said switch machine, a signal control circuit including the contacts of a signal control lever and for controlling said signals, and means for indicating over said switch control circuit the fact that said signal control circuit is energized and a signal has responded to such energization.

11. In a control system for railway switches and signals, the combination with a local office and a distant way station, a power-operated railway track switch at said way station, a signal for governing traffic over said track switch, a lever in said office for controlling said track switch, a lever in said office for controlling said signal, and an indicator in said office controlled to be energized when said signal is clear and including an energizing circuit closed only if said switch machine lever assumes an operating position and said signal lever assumes a signal-clear position.

12. In combination, a track section including a railroad track switch, a signal for governing traffic over said track switch, a switch machine for operating said track switch, a switch control lever, a signal control lever, a switch control circuit energized in accordance with said switch control lever for governing the operation of said switch machine, a signal control circuit energized in accordance with said signal control lever for governing the operation of said signal, and means opening both said switch control circuit and said signal control circuit to indicate an occupied condition of said track section.

13. In combination, a track section including a railroad track switch, a signal for governing traffic over said track switch, a switch machine for operating said track switch, a switch control lever, a signal control lever, a switch control circuit energized in accordance with said switch control lever for governing the operation of said switch machine, a signal control circuit energized in accordance with said signal control lever for governing the operation of said signal, means contemporaneously opening both said switch control circuit and said signal control circuit when said track section is occupied, and means responsive to the open condition of both of said circuits to indicate when said track section is occupied.

14. In combination, a track switch, a signal for governing traffic over said track switch, a switch machine for operating said track switch, a switch control lever, a signal control lever, a normally energized switch control circuit which is energized in accordance with the position of said switch control lever for governing the operation of said switch machine, a signal control circuit energized in accordance with said signal control lever for clearing said signal when said circuit is energized, means opening said switch control circuit when said signal control circuit is initially energized, means for reclosing said switch control circuit when said signal has cleared in response to energization of said signal control circuit, and means responsive to the energization of both of said control circuits for indicating the clear condition of said signal.

15. In combination, a track switch, a signal for governing traffic over said track switch, a switch machine for operating said track switch, a switch control lever, a signal control lever, a normally energized switch control circuit which is energized in accordance with the position of said switch control lever for governing the operation of said switch machine, a signal control circuit energized in accordance with said signal control lever for clearing said signal when said circuit is energized, means opening said switch control circuit when said signal control circuit is initially energized, means for reclosing said switch control circuit when said signal has cleared in response to energization of said signal control circuit, means always effective to open both said control circuits upon the occupied condition of a track section associated with said track switch, means responsive to the energization of both of said control circuits for indicating the clear condition of said signal, and means responsive to the deenergization of both of said control circuits for indicating the occupied condition of said track section.

16. In combination, a track switch, a switch machine for operating said track switch, a switch control lever, a normally energized switch control circuit which is energized in accordance with the position of said switch control lever for governing said switch machine, over-load means for said switch machine effective to remove the control of said switch machine from said switch control circuit when an over-load condition occurs, a detector track section associated with said track switch, means effective upon the occupied condition of said track section to open said switch control circuit, means responsive to the deenergization of said switch control circuit to restore the control of said switch machine to said switch control circuit, and means responsive to the deenergization of said switch control circuit to indicate at said switch control lever the occupied condition of said detector track section.

17. In combination; a track section including a railroad track switch; a signal for governing traffic over said track switch; a switch machine for operating said track switch; a switch control circuit for governing the operation of said switch machine, said circuit including a current source, lever contacts, a switch control relay and connecting wires; a signal control circuit for governing the operation of said signal, said circuit including a current source, lever contacts, a signal control relay and connecting wires; means opening said switch and signal control circuits when said track section is occupied; and means responsive to the contemporaneous deenergization of both said control circuits to indicate the occupied condition of said track section.
